UNITED STATES PATENT OFFICE.

ALEXANDER T. KASLEY, OF ESSINGTON, PENNSYLVANIA, ASSIGNOR TO WESTINGHOUSE ELECTRIC AND MANUFACTURING COMPANY, A CORPORATION OF PENNSYLVANIA.

TURBINE.

Original application filed December 12, 1921, Serial No. 521,872. Divided and this application filed April 23, 1923. Serial No. 634,067.

To all whom it may concern:

Be it known that I, ALEXANDER T. KASLEY, a citizen of the United States, and a resident of Essington, in the county of Delaware and State of Pennsylvania, have invented a new and useful Improvement in Turbines, of which the following is a specification, this application being a division of my application Serial No. 521,872, filed December 12, 1921, the latter application being a continuation in part of my application Serial No. 486,517, filed July 21, 1921.

My invention relates to steam or elastic-fluid turbines, and more particularly to low-pressure blading of the relatively wide type which receives steam or elastic fluid laterally and discharges it peripherally, and it has for its object to provide low-pressure blading of this character which shall be so designed as to operate with little, if any, vibration or deformation due to centrifugal bending stresses and which shall be capable of being easily and cheaply manufactured.

A further object of my invention is to provide, in connection with blading of the character designated, means which shall deflect the steam or elastic fluid from an axial toward a radial direction and which shall reinforce the blading structure.

In the drawings, forming a part of this application, Fig. 1 is a sectional view of a turbine with one form of my improved blading applied thereto; Fig. 2 is a perspective view on a large scale of one of the blades shown in Fig. 1; Figs. 3, 4 and 5 are sectional views taken along the line III—III, IV—IV and V—V, respectively, of Fig. 2; and Figs. 6 and 7 are diagrammatic views illustrative of certain features of my invention.

In the construction of steam or elastic-fluid turbines, particularly of the large high-speed type, it has heretofore been found to be necessary to provide the last row or group of rows of moving blades with large leaving angles in order to handle the large volumes of low-pressure steam or elastic fluid for the reason that, for a given speed, the blade height is limited by the allowable stress of the material of which the blade is made; and, of course, as the leaving angles are made larger the efficiency of the blading declines.

In the construction of high-power single unit turbines, difficulties have been met with 55 on account of excessive blade speeds due to the large rotor or disk diameter and the last row of tall moving blades necessary to pass the elastic fluid if the latter is to be discharged without too much residual energy. In the application of Henry F. Schmidt, Serial No. 482,768, filed July 6, 1921, and assigned to the Westinghouse Electric and Manufacturing Company, there is disclosed and claimed relatively wide last- 60 row blading which discharges peripherally or peripherally and laterally, thereby making it possible to provide high-power turbine units without encountering excessive 65 blade speeds. 70

The blading disclosed and claimed in said application of Henry F. Schmidt is relatively wide and it is capable of handling large volumes of low-pressure elastic fluid or steam and of discharging the latter at 75 small angles, thereby resulting in high blade efficiency, in improved turbine performance, and in making it practicable to construct large, high-speed turbines which operate with high efficiency. In the Schmidt turbine, adequate discharge area at small leaving angles is provided by having the steam or elastic fluid discharged peripherally or at the tips, thereby rendering it possible to make the discharge area equal at least to the 80 area swept by the inlet sides of the blades merely by choosing a width of blade which will serve this purpose.

It is characteristic of the Schmidt type of low pressure or exhaust moving blades that 90 they are relatively much wider than corresponding blading of the axial-flow type. In other words, the direction of flow of steam between the blades is changed and the steam is expanded and discharged peripherally so 95 that adequate discharge area may be provided, with the preservation of efficient discharge angles, merely by choosing a proper width. It will be obvious that a change in width is not accompanied by any change in 100 unit stress in the blading, whereas, with axial-flow blading, an increase in the discharge area is secured by making the blades taller or by choosing larger discharge angles. As axial-flow blading is made taller, 105 the centrifugal stresses increase until a

point is reached beyond which it is not safe to go and further discharge area may be provided only by gauging or providing the blades with larger discharge angles which 5 produce less efficient blading for the reason that the larger the discharge angle the larger becomes the axial component of the reactive effort. The capacity of axial-flow blading to handle large volumes of elastic 10 fluid efficiently is limited which is not true of blading of the wide type disclosed herein and in the Schmidt application aforesaid. Since width is a material factor in providing adequate discharge area with the latter 15 type of blading, it is to be understood that the terms "wide" and "relatively wide" are used in this specification and the appended claims to designate blading of this character which differs markedly over axial- 20 flow blading heretofore used. This type of blading is also capable of converting a greater portion of the kinetic energy of the elastic fluid or steam into useful work than can be converted by blading of the ordinary 25 type for the reason that, with the peripherally-discharging type of blading, the reactive force or effort is applied to portions of the blading moving at high effective blade speeds.

30 It is the object of my invention to improve the type of low-pressure blading disclosed in the application of Henry F. Schmidt, aforesaid, so that it may be more easily and cheaply made and may be of such 35 a design as to secure better operation. The contour of my improved blade is such that it may be easily rolled or drop-forged, or a row of blades may be built up of laminæ or sections and secured together in any suitable 40 manner. Better operation is secured by so designing each blade that the center of gravity thereof falls approximately midway of the circumferential thickness thereof, whereby centrifugal bending stresses 45 and possibly resulting deformation or vibration of the blades are avoided.

Referring now more particularly to the drawings for a detailed description of my invention, in Fig. 1, I show a turbine comprising a cylinder or casing 10 having bearings 11 of any suitable type for appropriate journal portions of the rotor 12. Any suitable energy-abstracting elements are carried by the casing and rotor for abstracting 50 energy by the expansion of steam or elastic fluid. For example, I show a stage 12 of the multi-velocity impulse type, comprising one or more nozzles 13 adapted to discharge steam or elastic fluid at high velocity into 55 the first row of impulse blades or buckets 14 from which the steam or elastic fluid passes to the re-directing blades or vanes 15 to be re-directed against the second row of impulse blades or buckets 16, followed by a 60 series of fractional stages comprised by the

stationary and moving rows of blades 17 and 18 carried by the cylinder or casing 10 and by the rotor 12, respectively. The steam or elastic fluid undergoes pressure-velocity conversion in the nozzle or nozzles 13 and the velocity energy is abstracted in two steps by the impulse blades or buckets 14 and 16. Thereafter, the steam is fractionally expanded in the stages comprised by the stationary and moving rows of 17 blades 17 and 18, and the steam then passes from the last row of moving blades 18 at a low pressure for action upon the blading of my improved form of low-pressure stage 19 comprising a row of guide blades 20 carried by the cylinder or casing 10 and a row of relatively wide blades 21 carried by the rotor 12.

The guide blades 20 discharge steam or elastic fluid between the blades 21 and the steam or elastic fluid is discharged from the latter peripherally or radially and laterally or axially. Each blade 21 has an inner radial or plane portion 22 having a suitable root portion 23 for attachment to the rotor 12. The radial or plane portions 22 are arranged in approximately axial planes and constitute supports for the outer curved, spoon-outline, or trough-like portions 24 constituting energy-abstracting portions for 95 the blades. The curved, spoon-outline or trough-like portions 24 extend from the inlet sides of the blades across the tops thereof, around the rear corners, and thence inwardly; and as illustrated in Figs. 1 and 2, 100 the inwardly-extending portions may merge into the inner radial portions 22, although it is to be understood that the inwardly-extending curved portion may extend inwardly to any desired extent. This form of curved, spoon-outline or trough-like construction permits of the discharge of steam or elastic fluid both peripherally and laterally at small angles.

As shown in Fig. 1, the casing or cylinder 10 is provided with a portion 25 which not only constitutes a support for the guide blades 20, but also serves to cover the outer portions of the inlet sides of the trough or spoon-outline portions 24 defining nozzle expanding passages between the blades, thereby preventing the cross-flow of steam or elastic fluid into the latter passages. A suitable plate 26 is secured to the rotor 12 and is arranged to cover the rear radial portions of the blades 21.

Each of the blades 21 is so designed that its center of gravity falls substantially midway of the thickness thereof, thereby avoiding the development of centrifugal bending stresses which might tend to cause it to vibrate or be deformed.

The inlet edges 21' of the blades 21 may be suitably inclined in accordance with the blade velocity, steam or elastic fluid veloc-

ity, and the angle of discharge of the steam or elastic fluid from the guide blades 20. See Figs. 2, 3, and 4.

Referring to the velocity diagram shown in Fig. 6, the vector a represents the velocity and direction of discharge of motive fluid leaving the guide blades 20, the vector b represents the blade velocity, and the vector c represents the relative velocity of the motive fluid with respect to the blades 21. The inlet side 21' should, therefore, be so curved as to be tangent to the incoming motive fluid, that is, to the vector c . In other words, the curvature of the inlet edges of the wide blades is determined by the direction and velocity of discharge from the guide blades and by the velocity of the moving blades.

In the apparatus described high grade efficiency is maintained by the preservation of small discharge angles. This will be apparent from diagrammatic Fig. 7, wherein the line d , tangent to the inner edge of the outer portion of the curved or spoon-outline portion, represents the direction of discharge of motive fluid and the line e is the tangent to the blade tip circle f . The angle α between the lines d and e is the angle of discharge and it will be noted that it is relatively small.

Apparatus made in accordance with my invention operates as follows: Steam or elastic fluid is expanded in the higher pressure stages of the turbine and it is discharged therefrom into the last low-pressure stage 19, having the relatively wide moving row of reaction blading which receives the steam or elastic fluid flowing in substantially an axial direction and discharges it peripherally or in a radial direction or peripherally and laterally. The steam or elastic fluid is expanded and discharged from the nozzle passages, defined by the curved, spoon-outline, or trough-like portions of the wide blades, at small angles, the feature of discharging at small angles being possible due to the fact that the discharge area may be made sufficient merely by choosing a suitable width of blade.

It will be obvious to those skilled in the art that my new type of blade is capable of securing better turbine operation. My new blades are capable of handling large volumes of low pressure, elastic fluid or steam, of expanding the elastic fluid or steam to low pressures, of operating at high blade efficiency as the elastic fluid or steam is discharged at small angles and the reactive effort of the high velocity elastic fluid or steam is applied to the blade portions moving at high effective speeds, and of operating at high speeds as the discharge area is secured by increasing the blade width instead of height. By using my wide exhaust blading, it is therefore possible to construct

large, high-speed turbine units and units which operate more efficiently than heretofore.

While I have shown my invention in a single form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In an elastic-fluid turbine, a row of peripherally-discharging moving blades having lateral inlet edges which are substantially tangential to the direction of incoming elastic fluid.

2. In an elastic-fluid turbine, a low-pressure stage including a last row of moving reaction blades having inner radial and outer curved portions adapted to receive elastic fluid axially and to expand and discharge it peripherally and laterally and means for blocking the inner portions of the outer radial edges of the blades.

3. In an elastic-fluid turbine, a low-pressure stage including a last row of relatively wide moving blades adapted to receive elastic fluid axially and to discharge it peripherally, and means for blocking the inner portions of the outer radial edges of the blades.

4. In an elastic-fluid turbine, a row of blades adapted to receive elastic fluid at one side and comprising inner substantially plane portions and curved energy-abtracting portions at the tips and at the other side.

5. A turbine blade comprising an inner substantially plane portion and a curved energy-abtracting portion at the tip and at one side.

6. In an elastic-fluid turbine, a low-pressure stage including a last row of relatively wide blades adapted to receive elastic fluid axially and to discharge it peripherally, each of said blades having an inner radial portion and peripheral and partial side trough portions, and blocking means cooperating with the outer radial side portions of the blades to assure the passage of elastic fluid between the trough portions.

7. In an elastic-fluid turbine having a casing, a rotor, and a plurality of stages carried thereby, a last-stage, including a last row of moving blades carried by the rotor, said moving blades having radial body portions and being curved peripherally and at the outer side portions and defining passages for the expansion of elastic fluid, whereby elastic fluid may be received axially and expanded peripherally and sidewise and the resulting velocity energy act reactively both upon the

peripheral and upon the side portions of the blades.

8. In an elastic-fluid turbine, a last row of moving reaction blades each having an inner radial portion and an outer spoon-outline or trough-like portion merging into a side spoon-outline or trough-like portion, the spoon-outline or trough-like portion diminishing inwardly radially and merging into said radial portion.

9. A turbine blade of the reaction type having an inclined radial inlet edge and an inner radial portion bounded, in part, by a spoon-outline or trough-like portion extending from the inlet radial edge and diminishing at the outer radial edge and merging into the radial portion.

10. In an elastic-fluid turbine, a last row of moving reaction blades, each comprising an inner radial portion bounded, in part, by an outer spoon-outline or trough-like por-

tion extending from the inlet radial edge and diminishing inwardly radially at the outer radial edge and merging into the radial portion, and means for blocking the outer radial portions of said blades.

11. In an elastic-fluid turbine, a last row of moving blades, each comprising an inner radial portion and an outer spoon-outline or trough-like portion extending from the inlet radial edge and diminishing inwardly radially at the outer radial edge and merging into the radial portion, the outer portions of the spoon-outline or trough-like portions defining passageways for the expansion of elastic fluid peripherally and sidewise, and means for blocking the outer edges of the radial portions of the blades.

In testimony whereof, I have hereunto subscribed my name this nineteenth day of April, 1923.

ALEXANDER T. KASLEY,
